UNITED STATES PATENT OFFICE.

HAROLD M. SCHEIBE, OF WILKINSBURG, PENNSYLVANIA, ASSIGNOR TO WESTINGHOUSE ELECTRIC AND MANUFACTURING COMPANY, A CORPORATION OF PENNSYLVANIA.

CENTRIFUGAL SWITCH.

1,162,518.

Specification of Letters Patent. Patented Nov. 30, 1915.

Application filed June 17, 1910. Serial No. 567,453.

To all whom it may concern:

Be it known that I, HAROLD M. SCHEIBE, a citizen of the United States, and a resident of Wilkinsburg, in the county of Allegheny and State of Pennsylvania, have invented a new and useful Improvement in Centrifugal Switches, of which the following is a specification.

My invention relates to centrifugal switches such as are commonly employed in electrical devices in which circuit connections are made and interrupted at predetermined speeds and it has special reference to fan motors of the single phase alternating current induction type and to starting means therefor.

The object of my invention is to provide a switching device of the above indicated character which shall be simple and durable in construction, effective in operation and especially adapted for comparatively slow speed devices in which a heavy and positive contact pressure is essential.

It has been common practice, in single phase alternating current fan motor construction, to provide the motor with an auxiliary winding, of the short circuited shaded coil type, to assist in starting. However, in slow speed motors of this class, such as are frequently employed for ceiling fans, it has been customary to allow the auxiliary winding to be permanently connected in circuit, as no suitable switching device has been known which would operate satisfactorily at slow speeds. It is evident that unnecessary and undesirable power losses have therefore been sustained throughout the operation of motors of the kind just mentioned.

My invention embodies means whereby such an auxiliary winding may be short-circuited upon itself while starting and automatically open circuited when a predetermined running speed is attained, as will be hereinafter described.

According to my invention, the rotor spider of a fan motor is provided with a pivotally supported cam member, or finger, which is placed in its operating position by centrifugal force. The cam member is adapted to operate an unstable spring knuckle switch which is positively opened and closed by a spring when it is engaged by the cam member, after which no further contact between the members occurs. It

will be noted that centrifugal force supplies no operating effort whatever, but merely places the cam in its proper operating position. Furthermore, the spring knuckle toggle is adapted to maintain a heavy and positive contact pressure at all times until the switch is opened by the cam member, thereby insuring a good electrical contact.

In the accompanying drawings, Figure 1 is a view, partially in elevation and partially in vertical section, of a ceiling fan which embodies my invention. Fig. 2 is a bottom plan view of the rotor spider and associated cam member shown in Fig. 1, only a portion of the secondary winding and core being shown. Fig. 3 is a perspective view of the switching device, in which portions of the device are broken away, in order to show the various parts with clearness, and Fig. 4 is a diagrammatic view of the circuit connections of the motor.

Referring to the accompanying drawings in detail, a fan motor 1 comprises a stationary laminated primary member 2, that is rigidly secured to a suspension rod or shaft 3 and is provided with a main winding 4 and an auxiliary winding 5, and a rotatable secondary member 6 which is provided with a winding 7 of the squirrel cage type and with a plurality of fan blades 8. The secondary member 6 is adapted to rotate about the shaft 3 upon a ball-bearing 9.

During normal operation, the main winding 4 is connected to a suitable source of energy (not shown), and, during starting, the auxiliary winding 5 is short-circuited upon itself through a centrifugally operated switching device 10. When such predetermined speed is attained that the auxiliary winding 5 is no longer needed, said winding is automatically open-circuited, as herein-after described.

The centrifugally operated switching device 10, just referred to, comprises a cam member, or finger 11, which is pivotally mounted on the rotor spider 6, and a switching device 12, which is suitably secured to the stationary primary member 2.

The cam member 11 is curved in form and is pivotally secured at one end to the rotor spider by a screw 13. The free end 14 of the cam member 11 is of wedge-shape and is adapted to operate the switching device 12, as hereinafter described. A supporting

member 15, which is secured to the rotor spider 6, is disposed substantially at right angles to the mid-position of the cam member 11 and supports the weight of said cam member. A coil spring 16, one end of which is secured to rotor spider 6 and the other end of which is secured to the cam member at 17, is adapted to exert its tension upon said cam member in opposition to the action of centrifugal force.

The switching device 12 comprises a switch member 18 which is mounted upon a knife blade 19 and is provided with a coil spring 20 which is adapted to maintain said switch member in either its open or its closed position, a U-shaped supporting member 21, a stationary contact terminal 22 to coöperate with said switch member 18, and an insulating stop 23, to restrict movement in a counter clockwise direction. The switch member 18 may be made of sheet metal, which is bent in such manner as to provide parallel side pieces 24 and 25, having slots 26, in which the knife blade 19 is secured. A suitable contact terminal 27 and two cam-engaging projections 28 and 29 are likewise provided on switch member 18. The knife blade 19 is fulcrumed in suitable openings 30 and 31 which are provided in the side walls 32 and 33, respectively, of the U-shaped supporting member 21. The spring 20 is fastened to the bottom 34 of said U-shaped member 21 and is hooked over the knife blade 19 and maintained under tension.

It is evident that the spring knuckle toggle is in unstable equilibrium when in its dead center position, and that it is only necessary to cause the switch member 18 to be moved slightly to the one side or the other of the dead center in order that the spring 20 shall positively actuate said switch member to either its full open or its full closed position.

According to my invention, I cause the cam member 11 to throw the switch 18 across its central position at predetermined speeds and I make the free end 14 of said cam member of proper shape to force the toggle past its dead center position when said end engages either of the projections 28 and 29.

Assuming the various parts to be in positions shown in the drawings, and that the motor is to be started from rest with both the main and the auxiliary winding in service, the operation is as follows:

As the motor speeds up, the centrifugal force, acting upon the cam member 11, gradually increases until it is sufficient to overcome the tension of spring 16, whereupon the cam member is thrown out to the position indicated in dotted lines in Figs. 1, 2 and 3. In this position, the cam member engages the projection 28 of the switch member 18 and forces said switch member down beyond its dead center position. The

spring 20 then positively carries said switch to its full open position, and thus open-circuits the starting winding 5.

When the supply of power to the motor is discontinued, the centrifugal force which acts upon the cam member 11 gradually diminishes as the speed decreases, until the tension of spring 16 overcomes said force, and restores the cam member to its original position. In this position, engagement with the projection 29 of the switch member 18 takes place and said switch member is thrown to its closed position against the stationary contact terminal 22. The auxiliary starting winding is thus short-circuited and the motor is again in condition for starting. It will be noted that after the cam member 11 comes into engagement with the switch member 18, the latter is immediately operated to either its full open or its full closed position and no further contact between said members occurs.

It will, of course, be understood that while I have shown and described a centrifugal switching device of specific construction, as applied to a fan motor of a particular type and winding, other commercial devices may be readily and advantageously equipped with said switching device for various purposes, and modification in size, arrangement and structure of parts, may be effected without departing from the spirit and scope of my invention.

I claim as my invention:

1. A switching device comprising relatively stationary and rotatable members, a cam member pivotally mounted on said rotatable member and adapted to be moved to one of its operative positions by centrifugal force, a spring opposing such action, a switch member having knife edge bearings and a spring adapted to actuate said switch member on either side of its dead center position, said switch member being mounted upon the stationary member and adapted to be engaged by said cam member at predetermined speeds of revolution and to be forced thereby to either side of its dead center position, the operating effort being supplied by the momentum of the rotatable member.

2. The combination with relatively stationary and movable members, of a switching device mounted on the stationary member in unstable equilibrium, a spring adapted to operate said switching device on either side of its dead center position, and a pivotally supported centrifugally operated cam member secured to the movable member and adapted to actuate said switching device to one side or the other of its dead center position, in a plane that is transverse to the plane of action of centrifugal force on said cam member, in accordance with predetermined speed conditions.

3. A switching device comprising relatively stationary and rotatable members, a switch member mounted on the stationary member which comprises a stationary contact terminal, a movable coöperating contact member provided with two projecting cam-engaging members, a knife blade upon which said contact member is supported, a suitable bearing member for said knife blade, a coil spring hooked over said knife blade and secured to said bearing member, and a cam member or finger pivotally mounted on the rotatable member, and adapted to be placed by centrifugal force in position to engage the one or the other of said cam-engaging projections under predetermined speed conditions. 15
- 5 In testimony whereof, I have hereunto subscribed my name this 10th day of June, 1910.
